CAP IRONER

Meyers M. Berger, Youngstown, Ohio

Application June 3, 1940, Serial No. 338,488

3 Claims. (Cl. 223—15)

This invention relates to a cap ironer.

The principal object of this invention is the provision of a cap ironing machine so formed that workmen's caps, such as are commonly worn by various mechanics and railway employees, may be simultaneously ironed, shaped and sized with a single operation of the machine.

A further object of the invention is the provision of a cap ironer upon the heated cap shape blocks of which a workman's cap may be placed and which will, upon manual release of a conveniently positioned pedal, properly iron and shape a cap thereon.

A further object of the invention is the provision of a cap ironer the ironing blocks of which are positioned one movable and one stationary so that a cap positioned thereon when they are in closely associated relationship will be properly sized and ironed due to a stretching action resulting from the movement of the movable block in relation to the stationary block.

A further object of the invention is the provision of a cap ironing machine the block portions of which are suitably heated so as to effect a rapid ironing action on caps positioned thereon.

A still further object of the invention is the provision of a cap ironing machine provided with a plurality of cap ironing units upon which several workmen's caps may be simultaneously ironed and shaped.

Specifically, the cap ironing machine is shown and described herein in its simplest form wherein a single pair of cap ironing blocks are positioned in an appropriate structure so that one of the blocks may be moved in relation to the other and wherein the movable block is under spring tension so that it normally is urged away from the stationary block except at such times as it is moved into close association therewith by the manipulation of a conveniently placed manually operated pedal. The cap ironing blocks are positioned in a cabinet structure which encloses the various levers and arms essential to the operation of the cap ironing machine and a centrifugal impeller type fan or any other form of blower may be and preferably is positioned in a side or back wall of the cabinet so that air is continually circulated through the cabinet and upwardly through the area between the heated ironing blocks so as to effect a rapid drying action on the cap being ironed. The cap ironing blocks are both heated, in the disclosure made herewith, by steam lines and provision is made for return lines for the condensate.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

By referring to the drawing it will be seen that a cross sectional side elevation of the cap ironing unit has been shown wherein a frame forming a cabinet 10 provided with a plurality of legs 11 and a top portion 12 has positioned thereon in a stationary manner a half circular heated cap block 13 the uppermost portion of which is of slightly larger diameter than the lowermost portion so that the crown of a workman's cap will fit snugly thereover. Positioned in front of the stationary cap ironing block 13 and in movable relation thereto and in movable relation to the cabinet top 12, as the same is movably positioned in an appropriately shaped opening therein, there is a matching half circular cap ironing block 14 of the same size and description as the stationary block 13 and so formed and shaped and positioned that it may be moved into closely associated relationship therewith, in order that a workman's cap may be placed over the enlarged upper portions of these blocks 13 and 14 so that the crown of the cap is filled and shaped by the enlarged upper portions of the blocks and so that the head band of the workman's cap is positioned about the neck portions of the blocks as shown in broken lines in the drawing. In order that the movably positioned cap ironing block 14 may be moved away from the stationary cap ironing block 13 it is positioned in the cabinet like frame 10 by means of a supporting arm 15 which is pivoted at a point 16 to a cross member of the frame 10. Associated with this supporting arm 15 there is a plurality of links and levers as hereinafter specifically described which connect it to a pedal 17 which is itself pivoted at a point 18 to the cabinet like frame 10. The links and levers connecting the pedal 17 to the support arm 15 supporting the half circular movable cap ironing block 14 comprise a horizontal link 19 which establishes connection between a pivot 20 on the support arm 15 and a pivot 21 on the uppermost end of an L shaped lever 22 which is in turn pivoted at the junction of its arms to a cross member 23 of the cabinet like frame 10 at a

point 24. A link 25 comprising a pull rod is pivoted to the shorter arm of the lever 22 at a point 26 and to the pedal 17 at a point 27 so that downward motion manually imparted to the pedal 17 results in the downward movement of the pull rod link 25 and the horizontal movement of the horizontal link 19 thus effectively moving the support arm 15 and its cap ironing block 14 into close association with the stationary cap ironing block 13. In order that the cap ironing machine will normally tend to suitably size and stretch the caps being ironed thereon a coil spring 28 is operatively positioned between the pedal 17 and the cross member 23 of the cabinet like frame 10 so that the pedal is normally urged upwardly thereby thus normally urging the movable cap ironer block 14 away from the stationary cap ironer block 13.

In order that air may be introduced beneath the cap from the cabinet through the space between the ironer blocks 13 and 14 a fan or blower 29 is preferably positioned in the back or side wall of the cabinet 10 so that air is introduced into the cabinet and thus upwardly through the space between the ironer blocks 13 and 14 where it assists in drying the cap being ironed particularly that portion of the cap stretched between the ironer blocks. In this disclosure the blocks 13 and 14 are heated by steam coils 30 formed therein flexibly connected to steam and condensate lines 31 and 32, respectively.

In operation a machine would practically carry several of the ironer block assemblies so that a single operator could place a workman's cap on one, allow it to become stretched and the ironing action undertaken, and subsequently place caps on each of the other units of the machine returning from time to time to momentarily release the spring tension of the blocks on the caps and turn them so as to insure complete and full roundness in the finished cap and so as to insure a smooth head band finishing operation. The cap visors would have preferably been ironed in flat position prior to the shaping and ironing of the band and crown portions of the cap on the machine herewith described.

It will thus be seen that a cap ironing machine has been designed which will effectively size and shape workmen's caps so as to impart thereto a finished and workmanlike job and which will, by reason of its sizing operation, insure the continued fit of the workman's cap as compared with the heretofore known cap ironing operations wherein the workman's caps are ironed flat with no regard to appearance and no attempt at controlling the size of the head band. It is thus obvious that an important advance in the art of laundering and ironing workmen's caps has been made in the present invention. The term workmen's caps is intended to include various uniform caps and uniform cap tops several of which are provided with each uniform cap, and any other form of cap commonly cleaned or laundered the sizing and shaping of which is essential to a desirable appearance.

What I claim is:

1. A cap ironing machine comprising a cabi-

net like frame, a heated half circular appropriately shaped block positioned thereon, an oppositely disposed matching heated half circular block movably positioned adjacent thereto by means of a support arm pivoted at its lower end to a cross member of the said cabinet like frame, a pedal adapted for manual operation positioned in the said cabinet like frame and connected to the said support arm by means of suitable links and levers so that manual depression of the said pedal results in the movement of the movable half circular block into close relationship to the stationary half circular block so that a workman's cap may be positioned thereon, spring means positioned between a cross member of the said cabinet like frame and the said pedal for urging the said pedal upwardly so as to move the movable half circular block away from the stationary half circular block so that the workman's cap positioned on the said blocks will be suitably stretched and ironed thereby.

2. A cap ironing machine comprising a cabinet like frame, a heated half circular appropriately shaped block positioned thereon, an oppositely disposed matching heated half circular block movably positioned adjacent thereto by means of a support arm pivoted at its lower end to a cross member of the said cabinet like frame, a pedal adapted for manual operation positioned in the said cabinet like frame and connected to the said support arm by means of suitable links and levers so that manual depression of the said pedal results in the movement of the movable half circular block into close relationship to the stationary half circular block so that a workman's cap may be positioned thereon, spring means positioned between a cross member of the said cabinet like frame and the said pedal for urging the said pedal upwardly so as to move the movable half circular block away from the stationary half circular block so that the workman's cap positioned thereover will be suitably stretched and ironed thereby together with a blower positioned in a wall of the said cabinet like frame adapted to move air thereinto and upwardly in under the said workman's cap so as to assist in drying the same.

3. A cap ironing machine comprising a supporting frame, a heated half-circular appropriately shaped block positioned thereon, an oppositely disposed matching heated half-circular block movably positioned adjacent thereto by means of a support member pivoted to said supporting frame, means positioned in the supporting frame and connected to the said support member so that movement may be imparted thereby to the movable half-circular block so as to move the same into close relationship to the stationary half-circular block so that a workman's cap may be positioned thereon, spring means positioned between the supporting frame and the said support member for urging the said movable half-circular block away from the stationary half-circular block so that the workman's cap positioned on the said block will be suitably stretched and ironed thereby.

MEYERS M. BERGER.
